MOORING BARGE OR BUOY

Irwin Wyland Alcorn, Houston, Tex., assignor to
The Pure Oil Company, Chicago, Ill., a corpora-
tion of Ohio

Application December 7, 1948, Serial No. 63,983

2 Claims. (Cl. 114—26)

1

This invention relates to apparatus for mooring barges or ships in open waters. It also relates to a method of mooring a ship whereby its heading can be changed and maintained closely without casting off from the mooring points.

In underwater drilling operations for the production of oil, work frequently must be conducted from the decks of ships or barges and, as a consequence, the problems of mooring ships and barges securely in open water are somewhat accentuated. The principal requisite is that the working surface or deck be held stable at least in heading so that operations over the side can be conducted conveniently. Thus, if piles are being driven by means of a driver mounted on the deck of a ship, the pitching or rolling of the ship caused by the natural swell of the waves will not be a serious problem, provided the heading of the ship can be maintained with reasonable facility. Similarly, when an underwater well is producing oil, it is necessary to provide a vessel for storing the oil. This can be done either by running the oil into floating storage tanks, or floating barges or tankers. Where the ordinary oil tanker is used to collect oil produced from an underwater well, stability of working surfaces again requires that the ship be moored securely so that it can be headed into the wind. The mooring, therefore, requires that the heading be variable without interruption of working operations. Similar considerations apply to the heading of a ship from the deck of which the work of fabricating a derrick or over-water structure is being conducted.

Accordingly, it is a fundamental object of this invention to provide a mooring apparatus for a ship in open water so that a ship from which drilling operations are being conducted can be moored adequately.

It is a further object of the invention to provide a stable mooring buoy or barge.

It is a further object of the invention to provide a mooring barge which can be used for the storage of cargo, either liquid or dry, and which also can serve as a working platform from which some of the underwater operations can be conducted.

Other objects and advantages of the invention will in part be obvious and in part appear hereafter.

The invention, accordingly, includes a buoy having an essentially barge-like structure which is recessed at one end to mount a pivoted sheave, adjustable in height, and is provided with anchor means near the other end so that when used for

mooring a vessel, the strain to which it is subjected will be distributed efficiently between the sheave and the anchor means. The apparatus is also particularly adapted to a novel method of mooring a ship so that the ship is accurately held in its heading and can be adjusted therein, yet its moorings are sufficiently flexible to permit pitching and rolling of the ship with the natural swell of the waves around it.

The structure of the apparatus and the means for accomplishing the objects of the invention will be more clearly apparent from a study of the following specification, with reference to the drawings which include:

15 Figure 1 is essentially an isometric projection of the barge showing the general form thereof, including the pivoted mooring sheave, the anchor means, and covers for the several compartments within the barge;

20 Figure 2 illustrates in diagrammatic fashion the layout of lines in the novel method of mooring made possible with the structure of the instant invention.

Figure 3 is a fragmentary sectional view taken 25 along line 3—3 of Figure 1 showing structural details.

Referring now specifically to Figure 1, 10 represents the body of the barge which, it will be observed, has the basic form of a parallelepiped, 30 but has a recess 11 in one end thereof, and has the opposite end 12 finished off in inclined fashion. The purpose of the latter will appear in the subsequent portion of the description. On the surface of the barge, there is provided equipment for the various operations which become necessary when the surface is being used as a working platform. Thus, accessible to personnel on the working surface are lifting eyes 13, 14, 15 and 16 near the several corners of 35 the surface so that the barge can be seized by grappling hooks and raised from water or lowered into it. Likewise, at the several corners of the barge, there are provided cleats 17, 18, 19 and 20 for the fastening of such lines as may be 40 needed. The degree of compartmentation adopted in the barge will vary with the purposes for which the interior thereof might be desired to be used, for the barge can be used as a working surface and the interior for carrying cargo, either dry or liquid in form. A reasonable and 45 useful amount of compartmentation is indicated by the several manhole covers 21, 22, 23, 24, 25 and 26, which provide access to interior compartments into which the barge is divided by 50 bulkheads.

Also accessible from the surface of the barge are anchor lugs 27 and 28 which have matching anchor eyes 29 and 31 (29 only shown in Figure 1) located near the bottom of the barge. It will be seen that the arrangement is such that the anchor line can be suspended from the lugs, passed through the eyes and the two portions of the line joined beneath and to the rear of the barge, thereby aligning the resultant of these forces with the pull on the sheave. On the stern of the barge, there is provided a tow lug 32 by means of which the barge can be towed to the position where it is to be anchored. When operations from the barge have been completed, the vessel can be towed and beached ashore for the forward end of the vessel under towing conditions is the inclined face 12.

Within the recess 11 on the barge, there is mounted a base plate 33 carrying a hinge or pivot 34, which in turn carries a plate 35 mounting a sheave 36, which does not extend appreciably outside of the recess. To permit adjusting the position of the sheave to a raised or lowered level, an eye 40 and adjustable stops 37 and 38 along the inner sides of the recess are provided so that the chock 39 on which the sheave rests can be adjusted in level in accordance with the needs of the mooring operation.

For mooring a vessel, the use of the mooring barge or buoy is best understood by reference to Figure 2 wherein 50 represents a vessel, such as a tanker or a ship from which the drilling or pile driving operation is being conducted. For greatest stability, it is necessary that the ship be headed into the wind, the direction of which is indicated by arrow 51. The location of the operation is indicated by block 52 and working crane 53 mounted on the deck of the ship. To moor the ship securely, line 54 is passed from the point 55 on the deck of the ship, around the sheave 36 of the anchored mooring barge indicated as 56, and returned to the ship as 57 to be tied at point 58. A similar arrangement is made by means of line 59 passing from point 60 to barge 61 and returning as 62 to be tied at 63. From the stern of the vessel, similar ties can be made by means of line 64, barge 65 and line 66, and line 67, barge 68 and line 69.

From this method of mooring, it will be seen that the heading of the ship can be held squarely into the wind with considerable stability and the only motion to which it will be subjected will be the pitching and rolling produced by the swelling of the waves around it. When the wind shifts, the heading of the ship can be altered quite easily by adjustment of the several mooring lines. Thus, if the wind shifts to the direction indicated as 70, the ship can be headed into the wind by slackening line 54 and taking up line 57, while slackening line 59 and taking up line 62. At essentially the same time, the stern of the ship can also be brought around by slackening line 64 and taking up on line 66 and slackening line 67 and taking up on line 69. In this operation, it will be seen that the relative location of the derrick performing the operations over working space 52 is changed very little, if it is at all, thereby making it possible to continue work during the period the heading of the ship is being shifted.

It is apparent that the size of the apparatus used precludes manual operation of the various lines 54, 57, 59, 62, 64, 66, 67 and 69 in most cases, if not in all. Therefore, the best solution

in general is to provide a tying arrangement on the deck of the ship whereby one point, such as 55 of the pair 55-58 or 60 of the pair 60-63, is a power winch and the other a quick releasing clamp of conventional type used for clamping wire ropes. In the adjustment of a ship to keep it headed into the wind, therefore, it is seen that the operation of a winch to take up the rope will tend to produce the necessary adjustment in the heading of the ship. Proper adjustment of four winches operating simultaneously makes it possible to turn the ship in continuous movement. Adjustment of the position of the ship can also be made by releasing a clamp, letting out slack and taking in the slack on a corresponding winch. The advantage of using the quick release clamp and the hinged sheave on the buoy or barge for tying again shows up when the work operation has been completed and the ship has to be moved, for the problem of casting off from the mooring point is much simplified in that the wire clamp is released and the rope taken up by means of the power winch without the necessity of having to send personnel to the mooring barge to cast off. Because the movement of personnel from ship to platforms over water is one of the most difficult, hazardous and vexing problems in the underwater drilling and recovery of oil, the combination of the mooring barge with hinged sheave and the method of tying described constitute a marked advantage in recovery operations.

From this brief description of the invention and the embodiment thereof, it will be apparent that I have devised a new type of mooring barge or buoy and working platform for use in operations over open water and the invention should not be considered limited by the drawings, but rather illustrated thereby, without restricting the spirit or scope thereof.

What is claimed is:

1. A mooring barge comprising a watertight vessel having a recess in one end, said recess having two opposing sides and an open end, adjustable stops between said opposing sides of the open end of said recess, a chock movably fastened to said stops, a base plate at the rear of said recess, said base plate having pivotable means secured thereto holding a rotatable sheave, said chock contacting said pivotable means in supporting relationship.

2. A mooring barge comprising a watertight vessel having a recess in one end, a sheave disposed in said recess, means mounting said sheave for bodily pivotal movement relative to said vessel about a generally horizontal axis at the back of said recess, and an adjustable support means across the open part of said recess for positioning said sheave.
